TRAFFIC SIGNAL

Robert H. Worrall, Washington, D. C.

Application July 11, 1931. Serial No. 550,122

3 Claims. (Cl. 177—339)

(Granted under the act of March 3, 1883, as
amended April 30, 1928; 370 O. G. 757)

The invention relates to improvements in the method of and apparatus for cross roads traffic warning in which a car arriving at an intersection on either road by interrupting a beam of light causes a red light to flash in both directions on its intersecting road and to continue the warning until the car has had time to pass the intersection.

An object of this invention is to provide a method for warning a driver approaching an intersection on one of two intersecting roads that another machine is approaching the intersection on the other road.

Another object of this invention is to provide apparatus for the practice of my method.

According to my invention, a green light will ordinarily be exposed to traffic approaching the intersection on both roads in both directions. A machine arriving near the intersection will trip a relay cutting off the green light on the other road and cause a red light to flash in both directions on the other intersecting road. This flashing of the red light will continue long enough for the machine to clear the intersection and upon the discontinuance of the flashing red light the green light will be turned on again.

The circuits accomplishing these results are showing diagrammatically in the accompanying drawing.

Reference numbers 1, 2, 3 and 4 are sources of light with current supply for the same. These should all be in the center of the road at their respective locations. Light sensitive cells 5, 6, 7 and 8 should be located opposite their respective lights on the proper side of the road for traffic approaching the intersection.

Light sensitive cell 5 is in series with battery 9 and relay 13. Light sensitive cell 6 is in series with battery 10 and relay 14. Light sensitive cell 7 is in series with battery 11 and relay 15. Light sensitive cell 8 is in series with battery 12 and relay 16.

The control circuits are: a circuit comprising battery 17, solenoid of 18, and front contacts of 15 and 13 associated with road east-west, E—W; and a circuit comprising battery 19, solenoid of 20 and front contacts of 14 and 16, associated with road north-south, N—S.

The lighting circuits are: a circuit comprising battery 21, right contact of 18 and lights G, or battery 21, one of the left contacts of 18, appropriate jumpers 23 and lights R; and a circuit comprising battery 22, left contact of 20 and lights G', or battery 22, one of the right contacts of 20, appropriate jumpers 24 and lights R'.

The operation of this invention is as follows: Normally both control circuits are energized, holding the arms of 18 and 20 on the contacts which are not connected by jumpers to the other contacts, and lighting lights G and G'.

The interruption of the beam from source 1 by a car will open relay 13, deenergize the solenoid of 18 and allow a spring to draw the arm of 18 to the extreme left. As the car passes on, the relay 13 will be closed again and the solenoid of 18 energized, drawing the arm of 18 to the right which because of the dash pot will be a slow motion. When the arm of 18 was moved to the left the lights G were cut off and lights R lighted. As the arm of 18 moves slowly to the right it will cut off the red light while it is on the insulation between contacts but through the jumpers will light it again when the arm reaches the next contact. The result is that lights R are flashed on and off as the arm moves to the right and upon reaching the last contact the lights R are cut off and the lights G are lighted. The flashing red lights R show in both directions on the N—S road.

The same operation would result from the interruption of the beam from 3 by a car approaching from the east. Since the beams of light are across only the right side of each approach, but one beam of light will be interrupted by a car passing straight across the intersection or on entering the intersection and then turning either left or right.

In a similar manner a car approaching from either direction on the N—S road will cause the lights G' to be cut off and the lights R' to be flashed until the car is clear of the intersection, when light G' will be lighted again.

If cars approaching approximately simultaneously on the N—S and the E—W road, the lights R as well as the lights R' will be flashed. But the beams of light may be placed far enough from the intersection to give both cars ample time to stop before reaching the intersection and so avoid a collision. They can then proceed through the intersection in accordance with the customary traffic rules.

It is clear that the relays 13, 14, 15 and 16 could be operated by a number of different means, such as through the medium of a vacuum tube bridge circuit, where a change in capacity would cause a current to flow operating the relay; or an oscillating vacuum tube circuit where a change in capacity would cause the circuit to oscillate and current to flow operating the relay. The success-

ful operation of my invention does not depend upon the means employed for this purpose.

While in the foregoing there has been illustrated and described such combination and arrangement of elements as constitutes the preferred embodiment of this invention, it is nevertheless desired to emphasize the fact that interpretation of the invention should be conclusive only when made in the light of subjoined claims.

10 The herein described invention may be manufactured and used by or for the Government of the United States of America for governmental purposes without the payment of any royalties thereon or therefor.

15 I claim:

1. In a traffic signaling system for intersecting highways, a go indication and a stop indication for each highway, a movable switch arm for one highway, a second movable switch arm for the

20 second highway, a plurality of segments for each switch arm over which the switch arm is adapted to pass in contact and normally resting on one of said segments, means normally inactive for each highway, operable for a predetermined time

25 when actuated for moving a switch arm for that highway from rest position over its associated segments, means in one highway for connecting said indicating means to a switch arm and associated segments to display the go indication to the

30 other highway when the switch arm is at rest and for intermittently displaying the stop indication to that highway when the switch arm is moving, means for the other highway similar to the second named means, and vehicle actuated means in each highway for actuating the first named means for the corresponding highway.

2. In a traffic signaling system for intersecting highways, a go signal and a stop signal for each highway, traffic actuated devices for each approach to an intersection, a switch arm individual to each highway, spring means for actuating said arm to move it in one direction, electromagnetic

means for moving said arm in the other direction against said spring, a source of potential, normally closed contacts connecting said source of potential in circuit with said electromagnetic means, means comprising said traffic actuated devices for opening said normally closed contacts responsive to traffic actuation whereby said electromagnetic means de-energizes and permits said spring means to move said switch arm, a plurality of contacts associated with said switch arm for flashing the stop signal of the intersecting highway as said arm moves there-across responsive to the energization of the magnetic means, and means comprising another contact associated with said switch arm for actuating the go signal of the intersecting highway when the magnetic means is energized and said switch arm is returned to said other contact.

3. In a traffic warning system for two intersecting highways, a "go" signal and a "stop" signal for each highway, vehicle actuated electrical devices for each approach to the intersection, a movable switch arm for each highway, a plurality of contacts associated with each said switch arm so disposed that a terminal one of said contacts is in circuit with the "go" signal for the intersecting highway and the remainder are in circuit with the "stop" signal for that highway, an electromagnetic means associated with each switch arm so operated by said vehicle actuated electrical devices that said switch arms are held on or being returned to said terminal contacts when no traffic is passing, spring means for moving said switch arms across the remainder of contacts when said electromagnetic means are de-energized responsive to actuation of vehicle actuated electrical devices, and means connecting the vehicle actuated electrical devices and movable switch arm of one highway with the "stop" and "go" signals of the other highway.

ROBERT H. WORRALL.
